UNITED STATES PATENT OFFICE

114,084

DESIGN FOR A BADGE OR SIMILAR ARTICLE

Milton P. Link, Glen Rock, N. J., George P. de Mellier, Wantagh, N. Y., and Leslie F. Tillinghast, West Englewood, N. J., assignors to Great American Indemnity Company, New York, N. Y., a corporation of New York

Application February 4, 1939, Serial No. 82,788

Term of patent 14 years

To all whom it may concern:

Be it known that we, Milton P. Link, a citizen of the United States, residing at Glen Rock, county of Bergen and State of New Jersey, George P. de Mellier, a citizen of the United States, residing at Wantagh, L. I., county of Nassau and State of New York, and Leslie F. Tillinghast, a citizen of the United States, residing at West Englewood, county of Bergen and State of New Jersey, have invented a new, original, and ornamental Design for a Badge or a Similar Article, of which the following is a specification, reference being had to the accompanying drawing, forming a part thereof.

Figure 1 is an enlarged front elevation of a badge or similar article embodying the design, and,

We claim:

The ornamental design for a badge or similar article, as shown.

MILTON P. LINK.
GEORGE P. DE MELLIER.
LESLIE F. TILLINGHAST.
